PASSIVE REFLECTOR

Henri P. Coleman, Alexandria, Va., assignor to the United States of America as represented by the Secretary of the Navy

Application July 2, 1957, Serial No. 669,689

6 Claims. (Cl. 343—915)

(Granted under Title 35, U.S. Code (1952), sec. 266)

The invention described herein may be manufactured and used by or for the Government of the United States of America for governmental purposes without the payment of any royalties thereon or therefor.

This invention relates in general to a lens antenna and more particularly to a passive microwave reflecting lens utilizing an artificial dielectrical medium.

Electrical signal reflectors constructed of concentric rings of dielectric material with a varying dielectric constant are well known in the art as adaptations of the lens principle pointed out in R. L. Luneberg's "Mathematical Theory of Optics," pages 208-213. Such structure affords a reflector with excellent focusing abilities over a wide solid angle of scan and results in maximum antenna gain. This apparatus has been limited in its application because of the relatively large bulk and weight of the lens. Recently advances have been made in decreasing the weight of such antenna designs by use of artificial dielectric mediums but in many applications especially where size and weight are a critical consideration, the present lens apparatus is generally unsuitable. There are other types of antennas that do provide lightweight and compactness, for example, a corner reflector is a device which reflects a fairly well focused signal when the directional alignment is accurate. However, the corner reflector cannot even closely approach the uniform response of a reflecting lens over a wide angle since it does not reflect efficiently except at several rather limited angles, there being a marked deterioration of the response of a corner reflector at angular displacements of more than several degrees from the optimum response angles.

Therefore, it is an object of this invention to provide a reflector antenna having the characteristics and advantages of a solid dielectric lens without the inherent accompanying disadvantage of great bulk and weight.

Another object is to provide such a lens in a structure capable of expansion from a compact initial volume to a large fully-expanded volume.

Another object is to provide a method of creating an artificial dielectric medium of varying dielectric constant within a structure that is collapsible to a relatively small volume.

A further object of this invention is to provide a method of expanding such a lens from an initial volume to a large fully-expanded volume, such expansion to be uniform and accomplished without the possibility of entangling the lens components.

These and other objects of the invention may be more fully understood from a careful consideration of the following detailed description when taken with the accompanying drawing in which:

Fig. 1 is an illustration of the lens structure in the fully expanded operating position.

Fig. 2 is a configuration of the refraction and reflection of rays arriving at the lens as a collimated beam.

Fig. 3 is an illustration of the lens in the compact, non-expanded position.

2

Fig. 4 is an illustration of the lens when it is partially expanded.

In brief, the lens described herein comprises a plurality of extensible filaments of dielectric material with a plurality of conducting obstacles spaced in or on said extensible filaments at predetermined longitudinal intervals, said extensible filaments positioned longitudinally between two end plates in a predetermined variation of density and radius configuration to form a dielectric medium of suitable non-uniform dielectric constant. The aforementioned structure is enclosed by an envelope having a plurality of bellows-like pleats in planes parallel to the two end plates, said bellows-like pleats facilitating expansion along an axis normal to the two end plates and parallel to the extensible filaments. On one portion of the envelope is a reflector shield covering less than 180° of the circumference made suitable for reflecting collimated rays for electromagnetic energy arriving at the lens. Such rays are focused on the inner surface of the reflector shield. Such a lens will provide a microwave energy reflecting assembly with excellent focusing characteristics through a large solid angle of scan.

Referring now to Fig. 1, the structure of the cylindrical reflecting lens contains a plurality of extensible filaments 11 which are a dielectric made of plastic, paper or other suitable material. Filaments 11 support a plurality of conducting obstacles 11(a) such as imbedded metal pins, a metallic coating, or the like, which are positioned 15 lengthwise on or therein. The extensible filaments 11 are attached longitudinally between the circular end plates 12 which may be of any lightweight non-conductor or dielectric such as plastic, cardboard or other suitable material into which the extensible filaments 11 may preferably be molded. An envelope 13 of plastic, paper or any other material of suitable weight and strength is used to enclose the extensible filaments 11 and also to control the extension of the lens. At longitudinal intervals along envelope 13 are disposed a plurality of support rings 14 which may be tenuous members of a lightweight plastic such as polystyrene, a lapped seam of the envelope 13, or such means as will form an accordion-like pleat as an aid to uniform expansion. Also spaced longitudinally within the envelope 13, though not necessarily as numerous as the support rings 14, are a plurality of spacers 15 containing apertures 15(a) through which are threaded the extensible filaments 11. The spacers 15 may be of any lightweight substance such as plastic, paper or other suitable material and the apertures 15(a) through which the filaments 11 are threaded preferably correspond to the filament spacing on the circular end plates 12. The spacers 15 also contain vents 15(b) to allow an expansion medium such as air, carbon dioxide, or other suitable material, to flow throughout the envelope 13. To retain the prescribed pattern of location of the extensible filaments 11, the spacers 15 are situated longitudinally throughout the envelope 13. The extensible filaments 11 are threaded through apertures 15(a) in the spacers 15, thus maintaining proper location of the extensible filaments 11 in the expanded position and further serve the purpose of preventing snarling of the extensible filaments 11 when the envelope 13 is in the unexpanded position or being expanded. The spacers 15 also aid in giving the lens rigidity when such lens is fully expanded. The metallic reflector shield 16 may be achieved by a metallic coating or point on the surface of the envelope 13 and may be equal to or less than 180° in circumferential surface.

It is well known in the art that the normal energy propagational characteristic of a medium such as air can be altered by the placement of conductors therein. By selecting the size and spacings of such conductors, the

dielectric constant may be effectively altered substantially uniformly in a selected manner. To achieve suitable energy propagational characteristics in this invention the conductors 11(a) are spaced upon the extensible filaments 11 which are attached to the end plates 12 in the proper variation of density and radius configuration to simulate the alteration of dielectric constant required for a selected end result.

When the lens is fully expanded, the extensible filaments 11 form a cylindrical dielectric medium of varying dielectric constant n satisfying the Luneberg formula

$$n = \sqrt{2 - \left(\frac{r}{R}\right)^2}$$

where R is the lens radius and r is the distance from the center of the lens to the radial point where the dielectric constant is being determined. Then, as shown in Fig. 2, collimated rays of electromagnetic energy entering the lens will be focused at a point S diametrically opposite the entrance of the ray w passing through the center of the lens. The reflector shield 16 should preferably cover somewhat less than 180° in circumferential surface to prevent undue shadowing of the collimated rays such as y and z , farthest away from the radius vector ray w , and still give the lens its greatest solid angle of reflecting coverage. As taught by the art in "Modification of the Luneberg Lens to Perform as High-Gain Wide Angle Reflector," B. Gorr and F. S. Holt, Air Force Cambridge Research Center, Internal Memorandum, February 15, 1956, the shadow losses are negligible for a 90° reflector shield and increase as the reflector shield is enlarged in angular coverage. At 140° there is about 3 db loss in antenna gain and the shadow losses increase so rapidly thereafter as to make a larger angle reflector shield impractical. Therefore, 140° is recommended as a higher limit of the solid angle of scan and circumferential surface of reflector shield 16. Thus nearly all of the rays striking the reflector shield 16 at a point focus are reflected back through the lens to form a collimated beam of exceptional focus maximizing antenna gain.

The lens provides exceptional focus throughout a wide angular sector thereby eliminating the necessity of close directional alignment as is necessary with other apparatus. The lens further provides a radar marker or target for navigation or rescue signalling that requires no visual perception to precisely align such apparatus as a corner reflector since rotation of the lens through little more than half revolution will give a 360° coverage.

With reference to Figs. 3 and 4 it is apparent that the lens is made capable of expansion from a compact size Fig. 3 through partial expansion Fig. 4 to a large fully expanded volume of Fig. 1 by the elongation of the accordion-pleats of envelope 13. The support rings 14 typically used to form the accordion-pleats give the structure stability and control the uniform cylindrical shape while the envelope 13 is being expanded. The expansion of the antenna structure may be accomplished by applying a pressure differential within the envelope 13 either by chemical or physical means typically through a flexible tubular member 17 which can be closed off when desired. The lightweight of the structure makes normal respiratory pressure of the human body adequate for expansion. As the lens expands, the pressure differential passes through the vents 15(b) provided in the spacers 15 to all sections of the envelope 13, expanding each section and pleat smoothly and uniformly as shown in Fig. 4. The spacers 15 and support rings 14 furnish rigidity to the expanded envelope 13 and the spacers 15 also aid in maintaining the proper extensible filament 11 location. Further, by containing the extensible filaments 11 at several intervals throughout the envelope 13, the spacers 15 shorten the free lengths of the extensible filaments 11 in the unexpanded position thereby decreasing the possibility of their snarling or entangling during collapsed storage or during expansion of the lens.

Obviously, many modifications and variations of the present invention are possible in the light of the above teachings. It is therefore to be understood that within the scope of the appended claims the invention may be practiced otherwise than as specifically described.

What is claimed is:

1. A radiant energy reflector comprising, first and second end members, a plurality of conducting obstacles, extensible means for spacing said plurality of conducting obstacles at predetermined locations between the first and second end members, a longitudinally extensible enclosure cooperative with said first and second end members for containing said plurality of conducting obstacles, said enclosure being of non-conducting material, means for establishing a fluid pressure within said enclosure, and means for reflecting radiant energy passing within said enclosure.
2. A radiant energy reflector comprising, first and second end members, a plurality of conducting obstacles, extensible means for spacing said plurality of conducting obstacles at predetermined locations between the first and second end members, spacer means for retaining said extensible means between said first and second end members and substantially perpendicular thereto, each of said spacers containing a plurality of apertures for maintaining selected spacing between adjacent extensible means and expansion pressure vent-means for restricting the passage of fluid through the spacers, a longitudinally extensible enclosure cooperative with said first and second end members for containing said plurality of conducting obstacles, and means for establishing a fluid pressure within said enclosure.
3. In a microwave reflector lens, a plurality of conducting obstacles, a plurality of extensible dielectric filaments, means for spacing said plurality of conducting obstacles at predetermined intervals along the plurality of extensible dielectric filaments, filament spacer means, each of said filament spacer means having vent means and a plurality of apertures, each of the plurality of extensible dielectric filaments being threaded through a respective one of the plurality of apertures in each of said filament spacer means such that the plurality of extensible dielectric filaments are parallel to one another and in the form of a cylindrical dielectric medium having a dielectric constant whose magnitude varies along a radius through the center of the cylindrical dielectric medium, two end plates, the plurality of extensible dielectric filaments connected between the two end plates, means including bellows-like pleats cooperating with the two end plates for enclosing the space between the two end plates, said bellows-like pleats formed in planes parallel to the two end plates, means for reflecting radiant energy, said last mentioned means positioned between the two end plates such that the point of focus of any beam of rays within the solid angle of scan will fall on the inner surface of said last mentioned means.
4. A radiant energy reflector comprising first and second end members, a plurality of conducting obstacles, extensible means for spacing said conducting obstacles between the first and second end members, spacer means for positioning said extensible means between the first and second end members and substantially perpendicular thereto, each of said spacer means containing a plurality of apertures for maintaining said extensible means in predetermined relation in the planes of said spacer means, each of said spacer means containing vent means for permitting passage of fluid through each of said spacer means, an extensible enclosure cooperative with said first and second end members, means for establishing a fluid pressure within said enclosure, and means associated with said enclosure for reflecting radiant energy.
5. A radiant energy reflector comprising first and second end members, a plurality of conducting obstacles, extensible means for spacing said conducting obstacles between the first and second end members, spacer means

for positioning said extensible means between the first and second end members and substantially perpendicular thereto, each of said spacer means containing a plurality of apertures for maintaining said extensible means in predetermined relation in the planes of said spacer means, each of said spacer means containing vent means for permitting passage of fluid therethrough, an extensible enclosure cooperative with said first and second end members, means for establishing a fluid pressure within said enclosure, and reflecting means associated with said enclosure for reflecting radiant energy, said reflecting means positioned between the first and second end members such that the point of focus of any beam of rays within the solid angle of scan will fall on the inner surface of said reflecting means.

6. A radiant energy reflector comprising first and second end members, a plurality of conducting obstacles, extensible means for spacing said conducting obstacles between the first and second end members, spacer means for positioning said extensible means between the first and second end members, a plurality of apertures in said spacer means, each of said extensible means being threaded through a respective one of said plurality of apertures in each of said spacer means such that said ex-

15 tensile means are parallel to one another and in the form of a cylindrical dielectric medium having a dielectric constant whose magnitude varies along a radius through the center of the cylindrical dielectric medium, reflecting means for reflecting radiant energy, said reflecting means positioned between the first and second end members such that the point of focus of the beam of rays within the solid angle of scan will fall on the inner surface of the said reflecting means, and means 20 cooperating with said first and second end members for maintaining said extensible means in an extended condition.
